[57] CLAIM

The ornamental design for a child's disposable toilet seat, as shown.

DESCRIPTION

FIG. 1 is a perspective view of a child's disposable toilet seat showing our new design;

FIG. 2 is a top plan view thereof;

FIG. 3 is a front elevational view thereof;

FIG. 4 is another perspective view thereof showing the seat in an operative position; and

FIG. 5 is another perspective view thereof showing the seat in a folded position.
